UNITED STATES PATENT OFFICE.

HENRY H. ASHLOCK, OF SAN DIEGO, CALIFORNIA.

OIL-BURNER.

1,248,055.

Specification of Letters Patent.

Patented Nov. 27, 1917.

Application filed November 3, 1916. Serial No. 129,394.

To all whom it may concern:

Be it known that I, HENRY H. ASHLOCK, a citizen of the United States, residing at San Diego, in the county of San Diego and

5 State of California, have invented certain new and useful Improvements in Oil-Burners, of which the following is a specification.

My invention relates to improvements in oil burners for use in connection with cooking and heating stoves, ranges, boilers, furnaces and the like, more particularly to that class of burner which utilizes crude oil or stove distillate and steam in combination as a fuel. The objects of my invention are: 10 first, to improve the general form and construction of the oil burner patented by me June 8, 1909, Patent Number 924,216 for oil burners; second, to provide an oil burner in which steam is produced from water by 15 20 the burner itself for aiding in the fuel combustion and distribution of the heat; third, to provide a burner of this class with a covering that will protect certain portions of the burner and prevents its being over heated and warping, and, fourth, to provide a burner with a generator plate for generating gas from the oil until the water is converted into steam after which the oil is sprayed over the parts of fire brick and aiding 25 30 35 the combustion thus reducing the carbon and soot to a minimum, and, fifth, to provide an oil burner of this class which is simple and economical of construction, durable, easy to ignite, easy to operate and will not readily deteriorate or get out of order.

With these and other objects in view as will appear hereinafter, my invention consists of certain novel features of construction, combination and arrangement of parts 40 as will hereinafter be described in detail and particularly set forth in the appended claim, reference being had to the accompanying drawings and to the characters of reference thereon which form a part of this 45 specification, in which:

Figure 1 is a longitudinal sectional view through the middle thereof of the form of my device to be used in cooking stoves showing a portion in elevation to facilitate the 50 illustration. Fig. 2 is a top view thereof with the supporting plate 6 removed. Fig. 3 is a fragmentary top view of the same with said plate positioned thereon. Fig. 4 is a sectional view through the middle thereof of 55 the steam nozzle shown positioned relatively to the oil inlet pipe, a fragmentary portion

of which is shown. Fig. 5 is a front view of said steam nozzle shown positioned relatively to a fragmentary portion of the oil inlet. Fig. 6 is a longitudinal sectional view 60 through the middle thereof of a modified form of the burner adapted for use with furnaces and boilers. Fig. 7 is a transverse sectional view thereof through 1—1 of Fig. 6. Fig. 8 is a fragmentary top view thereof. Fig. 9 is a perspective view of the inclined generating plate and Fig. 10 is a perspective view of the modified form of burner without the portions of fire brick and the inclined generating plate. 70

Similar characters of reference refer to similar parts throughout the several views.

The pan 1, inclined generating plate 2, brick 3, steam pipe 4, oil pipe 5, and supporting plate 6 constitute the principal parts 75 of my oil burner.

The pan 1 is shallow and elongated in shape and it is provided with a pair of tapering ribs 1^a upon which is loosely mounted the inclined generating plate 2 which 80 is provided around its outer edge with a flange 2^a adapted to prevent the oil from running off at the edge. On top of this inclined plate 2 in the pan 1 is heaped a mass of broken pieces of fire brick. Mounted on 85 said pieces of fire brick and partially supported by said fire brick and the inclined generating plate 6 is the steam pipe 4, the one end of which communicates with any desired water supply and extends down 90 through the plate 6, and out over the pan 1 and the pieces of fire brick 3 and forming a loop over said pan in the course of the blaze from the burner and its other end extends backward to the opposite end of the 95 pan 1 at right angles and then over the middle to adjacent the center of the support 6 and it is provided on its extended end with the nozzle 4^a which is an ordinary pipe cap provided with a pair of slits therein placed 100 in horizontal position to permit the exit of steam from the pipe formed by the heat of the water in the pipe by the burner. The one end of the oil pipe 5 extends in a vertical position so that its end is adjacent to and 105 just over said nozzle 4^a positioned as shown best in Figs. 4 and 5 of the drawings. This oil supply pipe extends upwardly through the support 6 and to any oil supply reservoir as desired. The supporting plate 6 is 110 disk shaped and is provided centrally with a damper 6^a surrounding the oil pipe adapted

to provide and regulate the draft to the burner.

In the modified form of construction shown in Figs. 6, 7, 8, 9 and 10 of the drawings the pan 1 is provided with a hood 7 which incloses the burner except on one side thereof, the direction in which the blaze extends. In the top of this hood 7 the steam and oil supply pipes are supported instead of in the plate 6 in the other form of construction, and there is provided two apertures 7^a from the top side thereof for providing draft to the burner, and in the back side there is provided a damper 7^b for regulating the air to said burner. Otherwise the construction is the same as that described in the other form of burner.

Though I have shown and described a particular construction and a particular modified form thereof, I do not wish to be limited to this particular construction and its modification, but desire to include in the purview of my invention the construction, combination and arrangement substantially as set forth in the appended claim.

It is obvious that with this construction there is provided an oil burner which produces steam from water and uses the same in connection with the oil for fuel, and also for spraying or spreading the oil at the point of ignition to provide proper combustion and distribution of heat, that the pieces of fire brick protect the inclined plate and prevent its becoming overheated and

warping, that the steam and oil in the proper regulated quantities will provide a fuel that will produce a maximum of efficiency and a minimum of carbon or soot, that the device as a whole is simple and economical of construction, durable, easy to operate, easy to light and will not readily deteriorate or get out of order.

Having thus described my invention, what I claim as new and desire to secure by Letters Patent is:

In a device of the class described, the combination of an elongated pan provided with vertical ribs longitudinally therewith, an inclined generating plate supported by said ribs in said pan provided with an upwardly extending flange around its outer edge, fire brick mounted on said inclined plate, a water and steam conducting pipe mounted over said fire brick and plate, a nozzle at one end of the steam pipe provided with slotted apertures, and a fuel oil conducting pipe positioned so that its exit terminates just above and in front of said slotted apertures whereby steam is produced in said water conducting pipe by said burner and contacting with said fuel oil supply sprays the same and forms a combination oil and steam fuel.

In testimony whereof, I have hereunto set my hand at San Diego, California, this 28th day of October, 1916.

HENRY H. ASHLOCK.
